UNITED STATES PATENT OFFICE.

WILLIAM THOMAS COSGROVE, OF GARDINER, MAINE.

HAT OR CAP.

Application filed March 9, 1925. Serial No. 14,046.

My invention relates to improvements in hats and caps and one object is the provision of a head covering which will fit the head snugly and closely and while providing the necessary protection will retain the hair and prevent it from falling into the eyes, making the covering highly desirable for persons engaged in sports or athletics.

Another object of my invention is the provision of a hat or cap which can be easily adjusted or fitted to the head and prove a most useful article for male or female use, which can be made of any suitable material and which can be folded to occupy a very small amount of space to enable carrying in the pocket if desired.

Another object of my invention is the provision of head covering which will fit flat upon the head and hold the hair in proper position and which not presenting any round or protruding edges will prove very comfortable upon the head of the wearer.

Another object of my invention is the provision of a hat or cap which can be easily adjusted to suit the size of the head, which will afford the necessary protection while allowing proper ventilation, which can be easily transported and manufactured at a very small price, and which generally in every respect will produce an article which will fill a long felt want in a perfect manner.

With these objects in view my invention consists of a head covering embodying novel features of construction and arrangement of parts, substantially as described and claimed herein, and as shown in the drawing, wherein:

Figure 1 represents a perspective view of a head covering constructed in accordance with and embodying my invention.

Fig. 2 represents a plan view of the strip or blank from which the main or crown portion of my covering is produced, showing the manner of slitting the material, and

Fig. 3 represents a similar view with parts of the slitted portion of the blank being extended to illustrate how the manner of slitting produces the sections which form the crown of the hat or cap.

In carrying my invention into effect I use a blank or strip of leather or other suitable flat material which is slit at A, B and C, as shown in Figures 2 and 3, which provides the upper ends D, which are secured to the top caps E, the intermediate loops F, which are connected and strengthened by the in-

tersections G, and the lower ends H, which are secured to the head band J, which head band may if desired be provided with an adjusting buckle K and free end L.

From this construction it will be observed that slitting the blank or strip in the manner described provides the open crown portion composed of the upper loops M, the central loops N, and the lower loops O, which when connected to the cap pieces and band produces a crown which will completely fit the head and retain the hair in proper position while providing a very light head covering which will insure comfort and ease to the wearer.

The head covering can be used advantageously by male or female and is preferably made from a flat blank to fit flat and smooth upon the head and the intersecting connection is sufficient to produce the necessary strength to insure strength and durability and retention of the hat in proper form.

The advantages of my head covering will be readily understood and appreciated by all persons desiring an article of this character and it will be apparent that the covering can be made of any suitable material and in any color described, can be easily packed and transported and folded to be readily carried in a pocket, and can be produced at such a low price as to make its use a practical necessity where a light, comfortable head covering of this character is desired.

The hat or cap in accordance with my improvement may be made of any suitable material and in any desired color to suit the fancy and also the device may be molded from rubber of the desired size and shape to fit the head and in any condition a highly desirable article will be provided.

The hat or cap will prove most useful and desirable for athletes, motorists, factory workers, and in fact for any person male or female requiring a light, cool, comfortable head covering which will have a neat appearance and confine the hair and prevent it from falling over the eyes.

If desired the head covering may be provided with a visor or band as may be found desirable and convenient.

I claim:

1. A head conforming structure, consisting of a strip of suitable material provided with upper and lower slits and intermediate loops, the upper ends of the loops being drawn together and secured and the lower

ends of said loops being spaced apart, and a band secured to said lower ends and adapted to fit the head.

2. A head conforming structure, consisting of a strip of suitable material provided with upper and lower slits and intermediate loops, the upper ends of the loops being drawn together, a cap secured to and connecting said ends, the lower ends of said loops being spaced apart, and a head fitting band secured to said lower ends.

3. A head conforming structure, consist-

ing of a strip of suitable material slitted to provide upper and lower slits and intermediate loops, a cap securing the upper ends ¹⁵ of said loops in close relation, a band secured to the lower spaced ends of the loops and adapted to fit the head, and means to fasten the opposing ends of the strip, the whole forming an open head fitting crown. ²⁰ In testimony whereof I hereunto affix my signature.

WILLIAM THOMAS COSGROVE.
